WALL BRACKET FOR BOTTLES

Arthur H. Payson and Charles O. Duevel, Jr.,
Norwich, Conn., assignors to The American
Thermos Bottle Company, Norwich, Conn., a
corporation of Ohio

Application February 23, 1937, Serial No. 127,001

1 Claim. (Cl. 248—291)

This invention relates to wall brackets for bottles and is particularly desirable for use with vacuum bottles, which are designed to maintain their liquid contents at substantially the same 5 temperatures for long periods of time.

A principal object of the invention is to provide a bracket to support a bottle in parallel swinging relation to the wall to which the bracket is affixed, whereby the bottle may be turned for 10 the purpose of pouring therefrom liquid contents therein contained.

Another principal object of the invention is to lock the bottle to the bracket, which is a very desirable feature where the same is to be used 15 in public or semi-public places, and at the same time permit the bottle to be freely used.

Other objects will be apparent from reading this specification in connection with the accompanying drawings, in which

20 Figure 1 is a vertical side view, partly in cross section, of a bracket embodying our invention;

Figure 2 is a plan view looking down upon the bracket and bottle, the latter being fragmentarily shown;

25 Figure 3 is a vertical cross-section taken along the line 3—3 of Figure 1;

Figure 4 is a side elevation showing modified means for securing the bottle to the bracket; and

30 Figure 5 is a plan view of the bracket and bottle holder shown in Figure 4.

Referring now in detail to the drawings, in which similar characters refer to similar parts throughout, 10 represents a bottle having integrally secured thereto the bottle side of the bracket 11, having a recess 12, adapted to receive the coupling-rod 13, which connects the bottle side of the bracket 11 to the wall side of the bracket 31. This coupling 13 is revolvably supported in the bearings 14 of the wall plate 15. At the wall end of the coupling 13 and integrally mounted centrally thereon is a disk 16, which in conjunction with the inner side of the wall plate 15, has an annular ball race, in which are contained the bearing balls 17. The wall plate 15 has a recess 18 at its inner side to accommodate the disk 16, and is spaced from the wall 21 sufficiently to avoid interference of the wall with the movement of said disk. An annular flange 13' is provided on the coupling 13. The flange 13' is of greater circumference than the coupling passage in the face of the wall side of the bracket and serves to limit longitudinal movement of the coupling 13.

55 The coupling 13 has a circumferential groove

19 into which the bottom side of the plug 20 extends, the said plug being in threaded relationship with the bottle side of the bracket 11 for such purpose. Preferably this plug 20 is screwed down tight to the coupling 13, so as to make it unitary therewith, which is desirable when the coupling 13 is revolvable as shown in Figure 1. When, however, the coupling 13 is mounted in a fixed position, or in the event of the same binding so as not to be revolvable, 10 then the plug 20 is screwed down only far enough to occupy a sliding relationship with the bottom of the groove 19. The plate 15 may be secured to a wall or other upright support 21 in any convenient manner, as by the screws 22.

In Figures 4 and 5, a modified form of bracket is shown. In these views, the bottle side of the bracket is not integral with the bottle, as is the case in Figure 1. Here we have a coupling element 11' which in its inner construction is similar to the coupling element of the bottle side of the bracket 11 shown in Figure 1. It is understood that this bracket is otherwise of the construction shown in Figure 1, the details of which are not shown in Figures 4 and 5 because the showing thereof in said figures would be a mere repetition of the showing contained in Figure 1. Integral with the coupling element 11' is a band section 23, which is offset from the coupling element 11' by the link 24, which is secured to both the coupling element 11' and the band section 23. It is obvious that this link 24 may be omitted, and the band section 23 joined direct to the coupling element 11'. Another band section 25 is hinged at 26 to the band section 23, and the free ends of these band sections are so formed as to be adapted to be secured together by a pin 27, and locked at 28. In Figure 4, the bottle to which this form of bracket is particularly adapted is shown. Annular projections 29 and 30 40 extend outwardly from said bottle, so that their outside circumferences are greater than the inner circumference of the band sections, so as to secure the bottle against being withdrawn from the band, when the same is in locked condition. 45

Assuming that the bottle 10 has been supplied with a liquid, the bottle may be tilted to pouring position in a parallel plane with the wall to which the bracket is secured. To overcome any friction between the coupling 13 and the plate 50 15, in which said coupling is adapted to turn, ball bearings 14 and 17 are provided, the balls 14 carrying the coupling 13, and the balls 17 acting as bearings for the disc 16, the tendency of which would otherwise be to contact with the 55

inner surface of the wall plate 15, and rub against the same, due to the weight of the liquid filled bottle.

We have shown and described what we believe to be the best embodiment of our invention. We do not wish to be limited in patent protection, however, to the embodiment so shown and described, but what we desire to secure by Letters Patent is set forth in the accompanying claim.

10 We claim:

In a wall bracket for bottles or the like, an internally chambered support adapted to be affixed to a wall and having an aperture therethrough,

a revolvable coupling element extending through the aperture in said support, a disk secured to the inner end of said coupling element and extending radially therefrom, an annular flange on said coupling element exteriorly of the support, said disk and flange cooperating with the wall of the chamber of said support to maintain the revolvable coupling in the aperture of said support, and means for securing a bottle to the outer end of said coupling element.

10
